UNITED STATES PATENT OFFICE.

WILLIAM H. DAY, OF BOSTON, ASSIGNOR TO CHAS. W. CLIFFORD, TRUSTEE,
OF NEW BEDFORD, MASSACHUSETTS.

TELEPHONE-SIGNAL APPARATUS.

SPECIFICATION forming part of Letters Patent No. 240,308, dated April 19, 1881.

Application filed June 9, 1880. (Model.)

To all whom it may concern:

Be it known that I, WILLIAM HENRY DAY, of Boston, county of Suffolk, State of Massachusetts, have invented an Improvement in 5 Telephone-Signal Apparatus, of which the following description, in connection with the accompanying drawings, is a specification.

My invention relates to signal apparatus for telephonic circuits, and is embodied in an individual signal controlled by a mechanical controlling device operated with a step-by-step movement to allow a given signal to sound after a definite number of electric impulses and consequently step-movements.

15 The invention consists in a proper arrangement and combination of the parts, as herein-after described, to enable the signal to be given by a vibrating or automatic circuit-breaker bell operated in the main circuit, a mechanical locking device preventing a movement of the armature actuating the signal-controlling device with the step-by-step movement while the bell is sounding. A locking device, shown as the same one just described, also locks the bell-hammers while the step-by-step movement of the controlling mechanism is going on, so that the bell-hammer is prevented from movement when released by the controlling device at the proper time in its movement, and the signal is 25 not allowed to sound except when both the controlling mechanism is in the proper position and the locking device removed therefrom to lock and prevent further movement of the controlling mechanism.

30 As herein shown, the locking device is actuated by a polarized armature, locking the bell-operating armature while the current is in one direction, and the armature which actuates the signal-controlling device, and which may 35 be called the "step-by-step" armature while the current is in the opposite direction. The said polarized armature also carries a stop to engage and hold all the signal-controlling devices at a certain point, and thus give them a definite 40 starting-point all in unison, the said stop being disengaged by the movement of the said armature caused by a reversal of the current, the current then being in the proper direction to sound the bell, but the bells of all the instruments being at this starting-point engaged by

the controlling device, so that it is not until after the current has been reversed to operate the step-by-step armature and controlling device that the proper instrument can be operated by again reversing the current. 55

As herein shown, the step-by-step armature and the ones to operate the bell and locking device are all operated by the same electro-magnet, and the step-by-step and bell operating armatures are simultaneously attracted 60 and released by the said magnet, but only one of them is allowed an effective movement at a time, the other one being held motionless by the locking device.

Figure 1 is a rear elevation of a signal apparatus embodying my invention, the inclosing-case being removed; Fig. 2, an end elevation thereof; Fig. 3, a top view thereof, and Fig. 4 a detached view, enlarged, of the controlling device and stop to bring it in unison 70 with those of the other instruments.

The working parts are sustained on a plate, *a*, suitable to form the front of a case to inclose the said parts, the back of which, as indicated by the dotted lines, Fig. 1, supports 75 the signal-bell *b*. The main circuit enters at the binding-screw 2, passing therefrom by wire 3 to and through the coils of the operating electro-magnet *c*, and thence by wire 4 to the insulated adjustable back-stop *d* of the bell-operating armature *e*, whence it passes by the said armature and circuit-closing spring *f* thereon and supporting-spring *g* to the frame-post *h* and connected binding-screw 5. The said bell-operating armature *e* carries at its 80 upper end the bell-hammer *i*, and is also provided with a controlling-hook, *j*, shown as a pin extended back therefrom and bent at right angles to engage and be held by a flange, 6, on the controlling-disk *k* secured upon a shaft, 90 *l*, the said flange and hook preventing a sufficient movement of the armature under the attraction of the magnet *c* to break the circuit at *d f*. The shaft *l* and controlling-disk *k* thereon are rotated to bring a notch, 7, in the 95 flange 6 of the said disk opposite to the hook *j*, to allow the said hook and armature *e* to vibrate by a ratchet, *m*, on the shaft *l*, the said ratchet being engaged and rotated for a distance of one tooth by a pawl, *n*, on the step- 100

by-step armature *o* pivoted on a bracket, *p*, on the frame *a*, and provided with the retracting-spring *q* at each vibration of said armature to and from the poles *r* of the magnet *c*. The 5 pawl *n* is pressed into engagement with the ratchet *m* by a spring, *s*, and is stopped and locked upon the said ratchet at the end of its vibration by the adjustable stop *s*, a slight spring, *t*, acting to prevent backward movement of the ratchet *m*.

As the armatures *e o* are both operated by the same magnet *c*, it is obvious that the magnetization and demagnetization thereof would vibrate both the said armatures simultaneously 15 if both were free to move, and that consequently if such were the case and the disk *k* were properly set to allow the armature *e'* to vibrate, it would in its forward movement break the circuit at *d f* and allow the armature *m* to be retracted and move the disk *k* to again lock the armature *e*. This is prevented 20 by providing a locking device shown as a block, *u*, (see Fig. 3,) carried upon a bent arm, 10, connected with armature *v*, pivoted, at 9, on a post, *y*, secured to the plate *a*, and adapted to be moved by the said armature along the pole *r* of the magnet *c*, to be interposed between the said pole and one of the armatures *o* or *e*, according to the position of the said armature *v*, 25 which is polarized by the permanent magnet *x'* in the usual manner. When the block *u* is in one position to lock or stop the movement of the armature *e* and to leave the armature *o* free to move, a stop-pin, 11, on the arm 10 is 30 in position to engage a stop-arm, *w*, on the shaft *l* when it comes in proper position in the rotation of the said shaft. The arm *w* is so placed as to be engaged by the stop 11 when the armature *o* is not wholly back to its stop, 35 so that in the further vibrations of the said armature the pawl *n* does not pass over a new tooth, but passes backward and forward over the same tooth, being stopped in its vibration by the tooth last engaged, the shaft *l* and connected devices not rotating.

By causing the armatures *o* of the different instruments in the circuit to vibrate a few times more than what is normally needed to bring the arms *w* to the stops 11, any of the 40 shafts *l* and connected devices that may have fallen behind will be brought around to the same position with the others, and then by reversing the current the armature *v* will be thrown over, withdrawing the pins 11 from 45 and releasing the arm *w* and connected shaft *l*. This same movement unlocks the armatures *e* in the different instruments, but they are now all held by the disks *k*, there being in this position no notches 7 corresponding to 50 the hooks *j*, this being the starting-point for the step-by-step movement in all the instruments. The notches in the disks *k* of the different instruments are placed at different positions relative to the arms *w*, as usual in this 55 class of signaling-instruments.

The instruments being in this position, the operation is as follows: Supposing it is de-

sired to sound the signal in which the notch 7 is so placed as to come opposite the hook *j* after two movements of the ratchet *m* and 70 shaft *l*, the current will first be broken, allowing the armature *o* to be drawn wholly back, and move the arm *w* beyond the stop 11, as shown by the dotted line, Fig. 4, and then reversed to throw over the armature *v* and block 75 *u* to unlock the armature *o* and lock the one *e*. The circuit will then be broken, allowing the armature *o* to be retracted and revolve the ratchet *m* one tooth, and with it the shaft *l* and connected parts. This will bring a notch, 80 7, in one of the instruments opposite the hook *j*; but the armature *e* of that instrument will be prevented from vibrating on the next closure of the circuit to attract the armature *o* by the block *u*, or otherwise it would be attracted 85 and itself break the circuit at *d f*, and thus, besides sounding the bell of that instrument and giving a false signal, would operate the armature *m* to change the position of the shaft *l* independently of the operator controlling the 90 circuit by the usual current-reversing finger-key. The circuit will now be broken again to advance all the disks *k* another step, when the notch 7 in the disk of the instrument it is desired to signal will be placed in the proper 95 position, but the said signal-armature *e* will still be locked by the block *u*. The circuit is now closed by the other key, sending the current in the opposite direction, which will first 100 throw the armature *v*, which is lighter, and acts under the attraction of the magnet more quickly than the ones *o e*, and thus lock the armature *o*, to prevent a further movement of the shaft *l*, and at the same time release the armatures *e* of all the instruments, leaving the 105 desired one in which the hook *j* is opposite to the notch 7 free to move, operating automatically in the usual manner as long as the circuit is closed at the key, the armature *e* in all the other instruments being held by the unnotched portion of the flanges 6 of the disks *k*, and the signals thus remaining silent. After 110 the signal has been given the current may be again reversed and broken several times to bring all the arms *w* to the stop 11, and thus 115 insure that the signal-instruments all start properly in unison, the circuit then being ready for signaling again, in the manner just described.

As herein shown, the shaft *l* is provided with 120 two stop-arms, *w*, and the disk *k* with two corresponding notches, the signals being all operated by a semi-revolution of the said shaft, the number of instruments in the circuit being less than half the number of teeth on the ratchet *m*. As 125 herein shown the number operated in this way can be as many as six. When necessary to operate a larger number the disk *k* can be provided with but one notch, 7, or the said disks can be made, as shown in Fig. 4, with one of the said notches adapted to receive a movable slide, 12, shown as dovetailed to retain it in place where it closes the notch, so that the opposite notch 130 not closed by such a slide is the only one adapt-

ed to permit the bell-operating armature to vibrate. The shaft *l* may have but one stop-arm, *w*, or both stop-arms may be retained and the instruments brought to a unison during the operation of setting the controlling mechanism to ring a bell after a larger number of movements than what is required to turn the shaft *l* half a revolution. For example, if both stop-arms *w* are retained, and it is desired to ring bell No. 8, the circuit will be broken seven or eight times bringing the signals to a unison-point beyond the sixth notch, after which they will be properly operated, as before described, to advance them two steps farther, thus bringing the eighth notch in position, as desired.

This construction enables all the signal-instruments to be made alike, the controlling-disks having two notches opposite one another, which can be properly placed with relation to the stop-arms *w*. Both these notches will be left open if less than six bells are to be operated in a given circuit; but if the number of bells is greater than six one of the notches can be filled with a slide, 12.

25 The shaft *l* is shown extended out through the plate *a*, at 13, to enable a pointer to be attached to show the movement thereof in the usual manner.

I claim—

30 1. In a telephone-signal apparatus, a signal-controlling mechanism and an electro-magnet and its armature to actuate it, a signal-operating armature and a locking device to prevent the effective movement of either one of the said armatures while the other is in operation, substantially as and for the purpose described.

2. In an electric signal apparatus, a signal-controlling mechanism and actuating-armature to operate it with a step-by-step movement, combined with a vibrating automatic circuit-breaking armature and locking device to prevent movement of the said actuating-armature when the circuit is broken by the said vibrating armature, substantially as described.

3. In a telephonic signal instrument, an electro-magnet and vibrating circuit-breaking armature therefor to operate a signal, combined with a signal-controlling device to prevent the movement of the said armature except when the said device is in one definite position, and a locking device to prevent the movement of the said armature when left free to move by the said controlling device, substantially as described. 50

4. The combination, with a single electro-magnet and two actuating-armatures thereon, one to operate a signal-controlling device and the other to operate the signal controlled thereby, of a polarized armature and locking device operated thereby to lock one of the said actuating armatures while the currents flow in one direction, and the other of the said armatures when the currents flow in the other direction, substantially as described. 55

5. A signal-controlling device and actuating armature and stop-arm therefor, and a locking device to prevent or allow a movement of the said armature, combined with a stop connected and moved with the said locking device to engage the stop-arm when the actuating-armature is unlocked, and release the said stop-arm when the armature is locked, substantially as described. 60

6. The signal-controlling disk provided with notches to allow a signal to be operated at certain definite points in the revolution of the said disk, combined with detachable pieces to be inserted in the said notches when desired to render them inoperative, as and for the purpose described. 70

In testimony whereof I have signed my name to this specification in the presence of two subscribing witnesses.

WILLIAM HENRY DAY.
